UNITED STATES PATENT OFFICE.

JOSEPH FOSSEL, OF GRAFTON, MASSACHUSETTS, ASSIGNOR TO ALSATIAN MACHINE WORKS, LIMITED, OF BOSTON, MASSACHUSETTS, A CORPORATION OF MASSACHUSETTS.

COMBING MACHINE.

Application filed March 28, 1925. Serial No. 19,140.

My invention relates to that class of combing machines which comb tuft by tuft, for example a machine of the Heilman type, wherein the combing cylinder is hung horizontally and has fixed to its periphery one or more combing segments. In the Tunstall Patent No. 1,351,076 there is described a double-sided combing machine of this type, wherein there are two combing cylinders mounted side by side, each co-operating with the nipper mechanisms on its side of the machine, these nipper frames being mounted in two rows parallel with the cylinders and back to back to be operated alternately by a swinging arm or pendulum so that the nipper frames on each side of the machine are all performing the same duty at the same time, the nippers on one side of the machine being open while those on the other side are closed. My present invention comprises a new mechanism for thus operating the nipper frames which is equally applicable for use in connection with the double-sided combing machine as shown in said Tunstall patent and with a single-sided machine. I have described my invention particularly in connection with a double-sided machine, like the Tunstall, but do not limit it to such a machine, as it is applicable to other well known combing machines as will appear to those skilled in the art.

In the machine of the Tunstall patent, a series of stationary shafts are provided on each of which a nipper frame is hung and is caused to swing freely by a pendulum lever mechanism, and other mechanism is provided to operate the top comb. On my present invention, shown in a double-sided comber, there are two rockable shafts running the length of the machine one on each side, both rocked from a single source and each shaft carries a number of nipper frames keyed thereto so that the rocking of each shaft rocks all the nipper frames mounted in it and also causes the operation of the top combs which are connected with it. My invention, however, lends itself to use in a single-sided comber, that is, a comber in which a single rock shaft only with its nipper frames, etc., is used—as will be readily understood.

In my present invention I have reduced

the number of gears employed and have eliminated some of the details described in the Tunstall machine and have in other ways simplified the design of the machine while maintaining all of its many good points.

In the drawings I have shown in connection with my invention top combs and means for operating them such as is described in the Tunstall application, Serial No. 674,709, filed November 14, 1923, Patent No. 1,535,701, April 28, 1925, with the exception that in this application the top comb receives power directly from the same part as the nipper frames being tied to the rock shaft on which the nipper frames are mounted. Other top comb mechanism may be used or the top comb mechanism may be otherwise operated if desired.

My invention will be understood by reference to the drawings in which it is shown in its preferred form.

Figure 1 is an end elevation showing the preferred construction for operating the nipper frames in either a single or double-sided comber.

Figs. 2, 3 and 4 are sections on lines 2—2, 3—3 and 4—4, respectively, of Fig. 5, these views being taken looking in the direction of the arrow in each case.

Fig. 5 is a side elevation of the end of the machine which carries the gearing, etc., by which motion is given to the heads, and also a portion of one of the heads, and

Fig. 6 is a figure corresponding to Fig. 1, showing a modification of the mechanism of Fig. 1, the sprocket wheel, for driving the cylinder brushes, however, being removed.

For purposes of identification of the location of some of the corresponding parts in the said Tunstall patent and application, some of the parts are given the same reference numbers as in the said patent and application. A is a base and A², A³, A⁴ and A⁵ are frames to support the shafts, etc.

1 is the power shaft which carries a fly wheel 2 and pulley (not shown). 3 is a pinion on shaft 1 like the pinion 3 in the said Tunstall patent.

63, 63 are two shafts, each carrying combing cylinders (not shown) to co-operate with the nipper frames on the two sides of the machine as in the said patent. One of

these shafts carries the gear 651 in mesh with the pinion 3 and each shaft carries a gear 650 which gears are in mesh (see Fig. 2) so that the shafts 63 are rotated in opposite directions.

In mesh with the gears 650 are idler gears 113 which are in mesh with gears 114 on shafts *a* carrying a crank disk 1141 (as in the Tunstall Patent No. 1,394,054)—to operate the clutch mechanism *b* by which the detaching rolls are operated. The clutch *b* is mounted on shaft 921, 120 being the crank pin on the crank disk 1141 by which the throw of the link 115 operating said clutch mechanism is caused as in said patent.

In the said Tunstall Patent No. 1,351,076 each nipper frame is hung to swing on a stationary shaft 29 mounted in frames A^3 , A^4 , A^5 , etc., the movement being given to the nipper frames by means of a swinging lever 12 mounted on a stud 13 (see Figs. 3, 7, 8 and 15 of said patent). My present invention includes the elimination of the parts shown in Fig. 15 of said patent and the mounting of one shaft 29 on each side of the machine in such a manner that each will be rocked and carry with it the nipper frames which are keyed thereto and, in order that they may be rocked positively, I have extended downward from each, arms 10 (see Figs. 1, 5 and 6) which are also keyed to the shafts 29, each arm being adjustably connected with a lever 12 fulcrumed on a stud 13 carried by the frame A^2 , and each carrying near its lower end a bowl 14 and at its extreme end a pin 15 to which is attached a spring 150 by which its bowl is kept in contact with a cam 16 mounted on the shaft 8. As shown one end of each spring 150 carries a hook 151 to engage the pin 15 and the other end a rod 152 which passes through a bracket 17 on the lower end of the frame A^2 and is held therein by nuts 18.

The cam 16 is suitably shaped to give the desired movements to the nipper frames and the top comb mechanism attached to shafts 29. In Fig. 1 the bowls 14 are engaging opposite surfaces of the cam. The cam surface, as shown on the right, has the largest radius and has a true radius through an arc of a sufficient length to permit the nipper frames and top combs to remain stationary while the cylinder needles are combing the tufts held by the nipper frames. To place the nippers in this position, the portion of the cam having the largest and true radius has thrown the lower end of the lever 12 outward against the pull of the spring 150, thus rocking its arm 10 to the left and turning the shaft 29, so that it has thrown its nipper frames to the left, that is, into closed position. The nipper frames thus nip the tufts to be combed, and remain stationary, while the largest and true radius of the cam

is in contact with the bowl 14. The cam surface, as shown on the left, and those portions of the cam surface joining the left hand portion with the true radial portion shown on the right, are so shaped as to allow the spring 150 to pull the lower end of the left hand lever 12 to the right, thus rocking its arm 10 to the left and turning the shaft 29, so that it will throw its nipper frames mounted thereon and top combs connected therewith outward with the nippers open, and also so shaped as to give the nipper frames and top combs an appropriate reciprocating movement, so that they may co-operate with the detaching rollers in detaching and piecing up the fleece.

The opening and closing of the upper nipper upon the nipper plate will be understood more particularly from Fig. 4 in which the lower nipper is marked 19 and the upper nipper 20. In the arms or side plates 23 of each nipper frame is mounted a shaft 21 which carries arms 22 on which the upper nipper 20 is fixedly mounted, this construction being such that the upper nipper is free to be given an oscillating movement. On the upper side of the arms 22 is mounted a plate 24 preferably of hardened steel. From the top of each frame are hung brackets 45 one on each side thereof corresponding to the similar brackets 45 in the Tunstall patent, but differently shaped therefrom because by my invention I am able to do away with shaft 13 of said Tunstall patent. In the lower end of two opposing brackets are adjustably mounted two levers 25 each of which carries at one end a bowl 26 adapted to rest upon one of the plates 24, the other end of each lever being attached to a spring 46, the other ends of these springs being attached to a convenient portion of the frame. The tendency of each of these springs is to pull upward that end of the lever 25 to which it is attached and hold the bowl 26 against the plates 24.

It will be seen from this description that upon the inward movement of one of the nipper frames, say that on the right of Fig. 4, the plate 24 will push against the rolls 26 and the corresponding upper nipper will be closed against the lower nipper by a yielding pressure as in said patent. The upper nipper is returned to open position by an arm 41 mounted on the end of the shaft 21 and a cam surface 42 on the frames as shown in said patent which engage when the frames are drawn into forward position as shown at the left of Fig. 4.

It will be seen from Fig. 3 that on these same shafts 29 are also keyed arms 32, a pair to each head or unit, which correspond to arms similarly numbered in said Tunstall application. To these arms, as shown, is attached a top comb 48 as in said application. Each shaft 29 thus causes the top comb to be

oscillated at the same time that the nipper frame is oscillated. Hence the nipper frames and the top combs on each side of the machine are caused to operate as a single structure and the swing of the top combs and the nipper frames may be adjusted by the one adjustment of the shaft operating mechanism and that adjustment may be caused in the following way: Referring to Fig. 1, it will be noted that the arms 10 are each slotted near its lower end as at 11 and in the slot is mounted a block 28 which is capable of sliding therein. A screw 30 passes through a lug 331 on the upper end of the lever 12 and through a swivel 31 mounted in the block 28, this screw being provided with suitable set nuts. The rotation of the screw 30 will change the location of the block 28 in the slot 11 and hence will change the location of the connecting point or pivot between the rocker arm 10 and the lever 12 so that the radius of swing of the arm 10 may be adjusted.

This same result may be secured by the modification shown in Fig. 6 where the lower end of the arm 10 is connected by a link 321 with the slotted end 33 of the straight lever 121 to which it is clamped by a screw block and clamp nut 34, an adjusting screw 35 being provided, as in Fig. 1, by which the position of the end of the link 32 may be adjusted with relation to the upper end of the lever 121 when the clamp nut 34 is loosened.

For this purpose the upper end of the lever 121 is provided with a lug 36 through which the screw 35 passes and nuts 37 are also provided by which this adjustment may be made and the parts thereafter set. As shown, the upper end of the lever 121 is thickened for strength.

It will be noted that the use of a cam 16 and springs 150 for the purpose of throwing the nipper frames enables the nipper frames to be given their desired movements positively such that each nipper frame may have an active forward movement and may also be held stationary while the combing cylinder is passing through the tuft, which is a very desirable feature as it allows the combing cylinder to perform its function with certainty and thoroughness. It allows it also to be given an appropriate movement to make it co-operate to the best advantage with the detaching rolls.

While it is undesirable in machines of this character that cams as a general rule should be used, the cam in this case is given such light work and is of such size that its wear will be negligible and this wear, if there be any, will not have the tendency to force the nippers into the combing needles. The upper nipper is yielding because of the use of the levers 25 and springs 46 as in the Tunstall comber.

It will of course be clear to anyone skilled

in the art that other means of swinging the shafts on which the nipper frames are positively mounted and other means of adjustment of the swing of the nipper frames may be used if desired, but I believe the above methods are each of them of very desirable and useful character.

The sprocket 38 shown in Figs. 1 and 5 is for connection by a suitable chain and auxiliary means with the brushes for cleaning the combing cylinders.

In Fig. 3 there are shown pinions 89 and 891 each of which is fixed on the end of a lower detaching roll and which are connected by the idler 90 on stud 91. Pinion 89 engages the gear 92 on the clutch *b* on shaft 921 so that the clutch *b*, operated as in said patents, drives pinion 89 which in turn drives the idler 90 and the pinion 891. The shaft 8 also carries a disk 105 which is attached to rocker arms 108 by slotted adjustable connections 109, these rocker arms 108 being attached to shafts 103 which are connected to the detaching roll motion as shown in Figs. 6 and 12 of the said Tunstall patent.

The operation of the top comb being fully described in the said application, it is not described here except to say for identification (see Figs. 3 and 4) that 140 is a link one end of which is connected to the rocker arm 32 and the other is connected to the link 141 free to swing on shaft 142, but adjustably attached thereto by means of the plate 144 and the adjusting screws 146. The link 141 is fixedly attached to the shaft 142 and to it is adjustably connected the arm 153. This mechanism is duplicated on the other side of the head and between the arms 153 the top comb 48 is mounted so that the top comb will be reciprocated horizontally, the free arm 152 resting on the friction roll 156.

In Fig. 2 it will be noted that the gears 7 and 114 are slotted and show bolts *c* passing through the slots. For adjustment each shaft *a* and 8 has a disk *a*¹ and 81 fixedly attached thereto. The gears are attached to these disks by the bolts *c*. Thus the position of the gears on the shafts may be adjusted.

It will be seen that while as shown in the drawings the nipper frames on both sides of the machine are operated alternately, the cam may operate either one of the sides alone as the nipper frame and top comb mechanisms are entirely independent of each other. Hence, as will be clear, my improvement is not essentially upon a double-sided comb, but comprises a nipper-operating mechanism which may be duplicated for use in a double-sided machine, for example in the way above described and operated by a single cam or the like. If the machine is built as a single-sided machine, the nipper frame and top comb may equally well be operated without change.

In any case the nipper frame always comes back to the same point over the combing cylinder, this point being controlled by the shape of the cam surface. It must be remembered that the fibres on which the nipper frames act are very minute in character and a very slight change in the inward throw of the nipper frame will vary the relation of the nippers to the combing cylinder, which would result in imperfect combing.

While I have described my invention as used in a particular structure, which is the best form thereof now known to me, I do not mean to limit myself to the details shown as it may be embodied in other forms as will clearly appear to those skilled in the art.

What I claim as my invention is:

1. In a combing machine, an oscillatory shaft and means for oscillating it, a nipper frame fast thereon to swing therewith and comprising a lower nipper fixedly mounted therein and an upper nipper mounted to swing therein, and means adapted to cause the closing of one of said nippers upon the other during a portion of the swing thereof.

2. In a combing machine, an oscillatory shaft and means for oscillating it intermittently, a nipper frame fast thereon to swing therewith and comprising an upper and a lower nipper, and means adapted to cause the closing of said nippers during a portion of the swing thereof.

3. In a combing machine, an oscillatory shaft and means for oscillating it intermittently, a nipper frame fast thereon to swing therewith and comprising an upper and a lower nipper, and means adapted to cause the closing of said nippers during a portion of the swing thereof and to hold them closed while said shaft and nipper frames are stationary.

4. In a combing machine, an oscillatory shaft and means for oscillating it intermittently, a nipper frame fast thereon to swing therewith and comprising an upper and lower nipper, means adapted to cause the closing of said nippers during a portion of the swing thereof, and a top comb and means for connecting it to said shaft whereby it will be given an intermittent horizontally reciprocating movement simultaneously with said nipper frames and said nipper frames being held in closed position and in fixed relation to said top comb during said stationary period.

5. In a combing mechanism, an oscillatory shaft, a nipper frame fast thereon, a top comb connected to said shaft, and means for oscillating said shaft, whereby said nipper frame and said top comb will be operated simultaneously, and means for oscillating said shaft.

6. In a combing mechanism, an oscillatory shaft and means whereby it is given

an intermittent oscillatory movement, a nipper frame fast on said shaft to be moved thereby, a top comb and means connecting it to said shaft, whereby it will be given a horizontal movement.

7. In a combing mechanism, an oscillatory shaft, and means for giving it an intermittent oscillatory movement comprising a cam, a nipper frame fixedly mounted on said shaft, a lower nipper fixedly mounted on said frame and an upper nipper mounted to oscillate in said frame, and yielding means whereby said upper nipper will be closed on said lower nipper with a yielding pressure.

8. In a combing machine, an oscillatory shaft, a plurality of nipper frames all mounted on said shaft to oscillate therewith and a single means for actuating said shaft whereby said plurality of nipper frames will be operated equally and simultaneously by the single actuating means said means comprising an arm fixedly attached to said shaft, a lever suitably mounted and attached at one end to said arm, its other end being located in the path of a cam, and said cam, whereby said lever and said arm will be rocked.

9. In a combing machine, an oscillatory shaft, a plurality of nipper frames mounted on said shaft to oscillate therewith, a plurality of top combs connected to said shaft, and a single means for actuating said shaft whereby a plurality of nipper frames and top combs will be operated simultaneously by a single actuating means to co-operate in presenting the lap for combing.

10. In a double-sided comb, two oscillatory shafts, nipper frames mounted on each shaft to oscillate therewith and a single means and connections between said single means and said shafts whereby the operation of said single means will oscillate both of said shafts and the nipper frames mounted thereon.

11. In a combing machine, an oscillatory shaft, a plurality of nipper frames all mounted on said shaft to oscillate therewith, each nipper frame comprising a lower nipper fixed thereto and an upper nipper adapted to swing therein, means whereby said upper nipper may be yieldingly held intermittently against said lower nipper, a single means for actuating said shaft, and connections whereby the oscillation of said shaft will cause the swinging of said nipper frames and of the upper nippers in said frames.

12. In a combing mechanism, a nipper frame and means for oscillating it comprising a turnable shaft, said nipper frame being fast thereon, and means for giving said shaft an intermittent oscillatory movement comprising a cam and means connected to said shaft and located to be operated by said cam, said connection being adjustable

whereby the length of the oscillations of said shaft and of said nipper frames may be adjusted.

13. In a combing mechanism, a nipper frame and means for oscillating it comprising a turnable shaft, said nipper frame being fast thereon, and means for giving said shaft an intermittent oscillatory movement comprising a cam and means connected to said shaft and located to be operated by said cam, said nipper frame having a lower nipper fixedly mounted thereon and an upper nipper pivotally mounted therein, means adapted to engage said upper nipper and close it against said lower nipper and hold it closed between the oscillations of said frame while said nipper frame is in combing position.

14. In a double-sided comber, two oscillatory shafts and a single means connected to each shaft whereby said shafts will be oscillated in the same direction simultaneously, nipper frames mounted on said shafts to be swung thereby.

15. In a double-sided comber, a pair of shafts, nipper frames located back to back and mounted to be operated by said shafts, and means comprising a cam and connections with said shafts to be operated by said cam alternately whereby said nipper frames will be swung toward and from a position to deliver the combed fibers to the detaching mechanism.

16. In a double-sided comber two oscillatory shafts and a single means connected to each shaft whereby said shafts will be oscillated in the same direction simultaneously, nipper frames mounted on said shafts to be swung inwardly and outwardly thereby, each nipper frame carrying an oscillatory upper nipper mechanism mounted

therein and spring controlled levers having fixed pivots, said levers being located to engage said upper nipper mechanism to close said upper and lower nippers with a yielding pressure while their nipper frames are swung inward.

17. In a combing machine, an oscillatory shaft, a nipper frame hung on said shaft to be oscillated thereby, said nipper frame carrying a lower nipper fixed thereto whereby said lower nipper will be positively oscillated and an upper nipper mounted to swing in said frame, and yielding means for closing said upper nipper against said lower nipper whereby the relative movements of said upper nipper will depend upon the location of the lower nipper in its oscillations.

18. In a combing machine having combing cylinders, an oscillatory shaft, a nipper frame mounted thereon to be swung thereby, means for oscillating said shaft whereby said nipper frame will always be brought to a fixed position adjacent to said combing cylinder.

19. In a combing machine having combing cylinders, an oscillatory shaft, a nipper frame mounted thereon to be swung thereby, means for oscillating said shaft whereby said nipper frame will always be brought to a fixed position adjacent to said combing cylinder and means for adjusting the length of swing of said nipper frame away from the combing cylinder.

20. In a combing machine, an oscillatory shaft having a plurality of nipper frames mounted thereon to swing therewith and a single means whereby the outward swing of the nipper frame may be adjusted.

JOSEPH FOSSEL.
